METHOD OF AND APPARATUS FOR PRODUCING ELECTRICAL SIGNALS REPRESENTING GRAPHIC INFORMATION

Donald F. O'Brien, 55 Fairview Ave., Watertown, Mass.

Filed Dec. 12, 1963, Ser. No. 331,339

10 Claims. (Cl. 178—18)

This invention relates to methods of and apparatus for producing electrical signals representing graphic information and particularly to methods of and transducers for producing voltages which are functions of the movement of a stylus.

This application is a continuation-in-part of my copending application Serial No. 146,719, filed Oct. 23, 1961, now abandoned, entitled Graphic Information Transducer.

Transducers of the general type with which the present invention is concerned are designed to introduce graphic information, in the form of a movement of a stylus, into an electrical system, primarily for the purpose of transmitting the information to a location remote from the transducer where it can be reproduced. Graphic communication systems of this type, also known as teleautographic systems, generally comprise a transducer including a planar writing surface and a stylus, an amplifier and a recording or reproducing device.

An object of the invention is to provide a novel and improved transducer for introducing graphic information into an electrical system, and a method utilizing said apparatus for producing electrical signals representing graphic information.

Heretofore, transducers employed in graphic communications systems have been either of two general types. In one type the stylus is connected through a mechanical linkage, such as a pantograph, to some type of electrical means such as a variable resistance or capacitance for varying the parameters of the electrical system. The mechanical coupling between the stylus and the electrical system not only represents a source of inaccuracy, error, and distortion of the information during transmittal therebetween of the stylus and electrical system, but the linkage itself tends to introduce distortion into the motion of the stylus. The other type of prior art systems suffer from the disadvantage that the voltage produced is dependent upon an electrical contact between different elements such as the movable stylus and a conductive writing surface or turns of two coils, the resistance of which contact is, of course, subject to variation.

The invention has as other objects the provision of a graphic information transducer the operation of which is independent of mechanical coupling between the stylus and other components of the transducer, or electrical coupling between conductors and is designed to introduce graphic information with substantially less error and distortion and with greater resolution than has been possible heretofore; to provide a transducer as described comprising a stylus having a substantially constant magnetic field associated therewith, a pair of coils having sensing portions lying in parallel overlying planes with the turns of the sensing portions of each coil perpendicular to the turns of the other and means supporting the stylus for movement in a plane parallel with the plane of the sensing portions; and to provide a transducer of the type described in which the magnetic stylus is constructed to minimize the effect of variations in the angle of the stylus with respect to the plane of the sensing portions of the coils.

Another characteristic feature of prior art transducers is that they function as integrators and produce voltages commensurate with the magnitude of the plane-rectangular or Cartesian, coordinates of position of the stylus. This information, while being suitable for controlling the opera-

2

tion of an X-Y recording or reproducing device, is considerably more difficult to amplify and to transmit than is derivative information.

Another object of the invention is to provide a transducer as described for producing derivative information in a form of voltages commensurate with the velocity of movement of the stylus with respect to two plane-rectangular coordinate axes.

As previously noted, the transducer comprises a stylus having a constant magnetic field associated therewith and two coils wound so that turns of each coil are perpendicular to the adjacent turns of the other coil. This ideal condition of perpendicularity may be difficult to achieve in actual practice and where turns of one coil are not perpendicular to adjacent turns of the other coil, a portion of the voltage generated in one coil by virtue of the motion of the stylus and its associated magnetic field will be coupled into the other coil by transformer action and result in the induction in the other coil of spurious voltages, that is, voltages which are not the result of motion of the stylus.

Still another object of the invention is to provide in a transducer of the type described, a novel circuit for cancelling out spurious voltages generated in the coils as a result of transformer action between the coils.

Other objects of the invention will in part be obvious and will in part appear hereinafter.

The invention accordingly comprises the process involving the several steps and the relation and order of one or more of such steps with respect to each of the others and the apparatus possessing the construction, combination of elements and arrangement of parts which are exemplified in the following detailed disclosure, and the scope of the application of which will be indicated in the claims.

For a further understanding of the nature and objects of the invention, reference should be had to the following detailed description taken in connection with the accompanying drawing wherein:

FIG. 1 is a schematic electrical diagram illustrating the construction and operation of a transducer embodying the invention and the method thereof;

FIG. 2 is a diagram illustrating somewhat schematically, the arrangement of coils comprising the transducer;

FIGS. 3 and 4 are front and side elevational views showing, in section, an arrangement of coils comprising the transducer;

FIG. 5 is a fragmentary view of a stylus comprising the transducer; and

FIG. 6 is a schematic electrical diagram of a circuit for eliminating spurious voltages caused by transformer coupling between the coils of the transducer.

The transducer embodying the invention comprises a substantially plane, rectangular writing surface covering sections of a pair of coils designated as an X coil and a Y coil. Each of the coils comprises a single conductor having a larger multiplicity of turns, sections of which are arranged in substantially parallel relation and lie in a plane. These sections of the coils lying in planes and termed the "sensing" sections, are arranged with the turns thereof in substantially perpendicular relation in the form of plane-rectangular X and Y coordinates, i.e., with the turns of the sensing section of the X coil extending parallel with the Y coordinate axis, and the turns of the sensing section of the Y coil extending parallel with X coordinate axis. The planar sensing sections of the coils are arranged in overlying, contiguous, parallel relation closely adjacent and parallel with the above-mentioned writing surface; and in a preferred form of the invention may be imbedded in the material comprising the writing surface.

In an alternative embodiment, each of the coils is provided with two sensing sections each lying substantially in

a plane and cooperating to effect an increase in the output potential of each coil. The other component of the transducer is a stylus comprising a permanent magnet which is moved with one end (a pole), in contact with the writing surface.

Reference is now made to FIG. 1 of the drawings wherein the operation of the transducer is illustrated schematically. The magnetic stylus is supported for movement in a plane by a planar writing surface so that the substantially constant magnetic field associated with the end of the magnet in contact with the surface intersects the coils and moves with respect to the perpendicular sensing portions of the X and Y coils. When movement of the stylus is transverse of the direction of one of the coils, a current is generated within that coil having a voltage commensurate with the speed of movement of the stylus in a direction perpendicular to the turns of the sensing section of the coil. Thus the voltage V_x , developed in the X coil can be expressed as a constant K times the velocity dx/dy in the Y direction. Similarly, the voltage V_y , developed in the Y coil, is expressed as $(K) (dx/dt)$. In this manner any movement of the stylus is represented by two voltages, the magnitudes of which are derivatives of the motion of the stylus in the X and Y directions. The graphic information is introduced into the transducer as a movement of a magnetic stylus and is converted by the transducer into two electrical signals representing derivatives of that movement. This method of producing electrical signals representing graphic information is particularly suited to the introduction of graphic information into a computer. Information input is more efficient and the memory requirements are reduced because constant monitoring and sampling of the signal is not required, since only changes in the signal require attention. These and other advantages of representing graphic information in a derivative form should be readily appreciated by one familiar with computers, for example, of the stored program digital type. The system of the invention has the additional advantages of: substantially infinite resolution since the signals are not dependent upon the size or location of a conductor or location and quality of an electrical contact; and substantially unlimited size because neither the electrical resistance of lengthy conductors, the strength and extent of a magnetic field, nor the dynamic range of devices (electronic) such as amplifiers, integrators, and the like, with which the transducer is coupled, is limiting factor.

In order to reproduce the graphic information, i.e., cause a recording instrument to duplicate the motion of the magnetic stylus, the derivative voltages are integrated to produce voltages which are commensurate with the magnitudes of the rectangular coordinates of position of the stylus; and these voltages may be employed to control the operation of a conventional X-Y recorder or other indicating or recording device. Integrating circuits, X-Y recorders and indicating devices such as oscilloscopes useful for this purpose are well known in the art and easily adapted to use in conjunction with the transducer of the invention.

In constructing and assembling the transducer, care is required to insure that adjacent turns of the two coils are perpendicular to one another in order to prevent coupling of the coils by transformer action in which the current flow in one coil, resulting from motion of the stylus, induces a spurious voltage in the other coil. Of course, parallelism in turns of the planar sensing sections of each coil and perpendicularity of the turns of the two coils are also important in order to insure uniformity, accuracy and freedom from distortion of the information. FIG. 2 illustrates one arrangement of the coils in which each of the coils is wound in a form of a substantially planar, open rectangle, and the two coils are arranged with perpendicular sections of the coil overlapping one another at two locations. The plane writing surface, which is preferably rectangular (and shown as a square),

is located at one of the two locations where sections of the coils overlap. Other arrangements are possible and include, for example, winding the coils around a support member in the form of a prism having five faces including a rectangular face which underlies the writing surface and supports the sensing sections of the coils, two other rectangular faces on which the return sections of both coils are supported in perpendicular relation, and two opposed triangular faces on which the return sections of one of the coils are supported.

Another arrangement comprises winding the coils around a support member in the form of a thin parallelepipedon. A preferred form of this arrangement is illustrated in FIGS. 3 and 4 and comprises means for magnetically shielding the return sections of the two coils from one another, from the planar sensing sections of the coils and from external magnetic effects. This is accomplished by the provision of shielding panels formed of a high permeability, magnetic barrier alloy such as mumetal or alloys sold by Perfection Mica Co. under the trade names "Netic" and "Co-nectic." The panels include a first spacer panel 10 lying between the planar sensing sections of the coils and the return section of the underlying or inner coil, designated for the purposes of example as the Y coil; a second spacer panel 12 disposed between the return section of the one (Y) coil and the return section of the other (X) coil; a bottom panel 14 disposed outside of the return section of the X coil; and four side panels 16 disposed around the sides of the two coils. The spacer panels function to prevent any unwanted coupling by transformer action involving the return portions of the coils, while the bottom and side panels prevent the development of spurious voltages due to external magnetic fields.

As previously noted, the stylus may be held in the hand and moved, in the manner of an ordinary pen or pencil, in contact with the writing surface which may, if desired, be formed of a material upon which the stylus will form a visible image. Since there is, of course, no way of precisely controlling the angle at which the stylus is held with respect to the writing surface and the plane of the sensing sections of the coils without inhibiting the natural writing motion of the operator, the end of the stylus which is held in contact with the writing surface is constructed so that the associated magnetic field assumes a form which eliminates or at least minimizes the effect of changes in the stylus angle on the voltage induced in the coils. This is accomplished, as shown in FIG. 5, by employing a cylindrical bar magnet having a tapered end in the form of a cone of revolution of an arc having a radius, designated R, which is 2 to 4 times the diameter of the stylus. The preferred radius of this arc has been determined empirically as being of the order of three times the diameter of the magnetic stylus.

It may be very difficult, as a practical matter, to wind the two coils in such a manner that all the turns of each coil are perpendicular to all the turns of the other coil, and for this reason some transformer coupling may exist between the coils resulting in the development of spurious voltages which cause distortion. A circuit for eliminating this distortion caused by transformer action between the coils is illustrated in FIG. 6. The circuit shown is designed to cancel out the voltages induced in one coil as a result of the flow of current generated in the other coil by developing a voltage at each coil which is equal to the spurious voltage and is of opposite sign; i.e., 180° out of phase. In the circuit shown, the X and Y coils, having the polarity shown, are connected to means such as amplifiers (not shown), and to ground. Each of the coils is connected through a pair of resistors R_1 and R_2 to one winding of a transformer. Each of resistors R_1 is connected serially with a sensing coil and one end of a transformer winding, while each of resistors R_2 is connected serially with a sensing coil, resistor R_1 and the opposite end of the transformer coil

which is grounded. Resistors R_1 and R_2 are provided for adjusting the parameters of the circuit so that the transformer develops at each of the sensing coils a voltage equal to and opposite in sign to the voltage induced in each coil as a result of coupling of the coils by transformer action. In a transducer in which the operating frequencies are relatively low, for example, 30 cycles per second, the values of the resistors may be determined in accordance with the equation

$$M \approx \frac{R_2 R_c}{R_1^2}$$

in which M is the percentage of the voltage in one coil induced by transformer action in the other coil, R_1 and R_2 are the values of the resistances, and R_c is the direct current resistance (relatively small) of a primary sensing coil. The circuit is bilateral for square writing surfaces and a transformer for a turns ratio of one, so that the selection of the proper values for the resistances will result in bilateral cancellation of spurious voltages. For non-square (rectangular) writing surfaces, bilateral cancellation of spurious voltages can be achieved by proper selection of either the diameter of the conductors comprising the sensing coils or the turns ratio of the transformer.

The operation of the transducer, like its construction, is quite simple, requiring only that the operator hold the stylus as if it were an ordinary pen or pencil and go through the motions of writing with the stylus in contact with the writing surface overlying the sensing sections of the coils. The stylus is free from the incumbrance of any of the mechanical linkages characteristic of many prior art systems, so that the movements of the stylus are unhampered and natural; and the coupling between the stylus and coils is magnetic rather than ohmic, and accordingly, is substantially more constant particularly when the stylus is shaped as shown and described in order to minimize or eliminate any effects resulting from changes in angle subtended by the axis of the stylus and the plane writing surface. All of the foregoing features cooperate in achievement of a transducer which is especially free of factors tending to cause distortion, inaccuracies and poor resolution and is capable of more faithful reproduction of the graphic information particularly handwriting being introduced.

Since certain changes may be made in the above apparatus and method without departing from the scope of the invention herein involved, it is intended that all matter contained in the above description or shown in the accompanying drawing shall be interpreted as illustrative and not in a limiting sense.

What is claimed is:

1. A graphic information transducer for producing electrical signals characterizing the motion of a member in a plane, said transducer comprising, in combination:

a pair of independent coils each having a sensing section with substantially parallel turns lying in a plane, said coils being arranged with said sensing sections separated from one another and held stationary in overlying face-to-face relation and with said turns of each of said sensing sections substantially perpendicular to said turns of the other of said sensing sections;

an input member having an associated magnetic field which is substantially unvarying; and

means providing a planar surface substantially parallel with said planes of said sensing sections for supporting said input member for movement in the plane of said surface relative to said sensing sections with said magnetic field intersecting said sensing sections; said input member being freely movable in said plane of said surface for inducing a voltage in each of said coils commensurate with the speed of movement of said input member relative to said each coil in a direction perpendicular to said turns of said sensing

section thereof and constituting one of said electrical signals.

2. The transducer of claim 1 in which said input member comprises an elongated cylindrical magnet having a tapered end section ending in a point and adapted to be held and moved manually with said point in contact with said surface.

3. The transducer of claim 2 in which said tapered end section is a cone of revolution of an arc having a radius which is 2 to 4 times the diameter of said magnet.

4. The transducer of claim 1 in which each of said coils includes a return section underlying said sensing section, and magnetic barriers are provided between said return sections and between said sensing sections and said return sections.

5. The transducer of claim 1 in which each of said coils is coupled with one winding of a transformer which produces a voltage at said each coil equal to and opposite in sign to the voltage induced in said each coil by transformer coupling between said each coil and the other of said coils.

6. A transducer for introducing graphic information into an electrical system, said transducer comprising, in combination:

25 a pair of coils each having a sensing section, the turns of which are substantially parallel and lie substantially in a plane; said coils being arranged with said sensing sections in overlying face-to-face relation and with said turns of each of said sensing sections substantially perpendicular to said turns of the other of said sensing sections; and

means for providing a magnetic field; said means being freely movable in two dimensions in a plane substantially parallel with the planes of said sensing sections with the latter located within said magnetic field for inducing a voltage in each of said coils commensurate with the speed of movement of said magnetic field relative to and in a direction perpendicular to the turns of said sensing section of said each coil;

each of said coils being grounded at one end and being coupled at its other end to a system, into which said graphic information is being introduced, through a pair of resistances and a winding of a transformer which produces a voltage at said each coil equal to and opposite in sign to the voltage induced in said each coil by transformer coupling between said each coil and the other of said coils, one of said resistances being coupled serially with said each coil and one end of said transformer winding and the other of said resistances being coupled serially with said each coil, said one resistance and the opposite end of said transformer winding which is grounded.

55 7. A sensing device for graphic information transducer comprising, in combination:

means providing a substantially planar writing surface; a first coil having a substantially rectangular sensing section including a multiplicity of turns arranged in parallel relation in a plane and positioned underlying, closely adjacent and parallel with said writing surface; and

a second coil having a substantially rectangular sensing section including a multiplicity of turns arranged in parallel relation in a plane and positioned underlying, closely adjacent and parallel with the plane of said first coil and said writing surface; said sensing sections of said coils being substantially coextensive and being positioned with the turns of each of said sensing sections substantially perpendicular to the turns of the other of said sensing sections;

each of said coils being grounded at one end and connected at its other end to an electrical system, into

which graphic information is to be introduced, through a pair of resistances to a winding of a transformer which produces a voltage at said each coil equal to and opposite in sign to the voltage induced in said each coil by transformer coupling between said each coil and the other of said coils, one of said resistances being coupled serially with said each coil and one of said transformer windings and the other of said resistances being coupled serially with said each coil, said one resistance and the opposite end of said transformer winding. 10

8. A graphic information transducer for producing two voltages having magnitudes representing derivatives of the motion of a member in mutually perpendicular directions in a plane, said transducer comprising, in combination:

a first coil having a sensing section including a multiplicity of turns arranged in side-by-side, parallel relation substantially in a fixed plane;

a second coil having a sensing section including a multiplicity of turns arranged in side-by-side, parallel relation substantially in a fixed plane closely adjacent and in face-to-face relation with said plane of said sensing section of said first coil;

said sensing sections being arranged in fixed positions with said turns of each of said sections perpendicular to said turns of the other of said sections;

an input member having an associated magnetic field which is substantially unvarying; and

means providing a planar surface substantially parallel with said planes of said sensing sections for supporting said input member for movement in the plane of said surface relative to said sensing sections with said magnetic field intersecting said sensing sections; said input member being freely movable in said plane of said surface for inducing a voltage in each of said coils commensurate with the speed of movement of said input member relative to said each coil in a direction perpendicular to said turns of said sensing section thereof and constituting one of said electrical signals. 40

9. In apparatus for reproducing the motion of a member in a plane, in combination:

a pair of independent coils each having a sensing section with substantially parallel turns lying in a plane, said coils being arranged with said sensing sections separated from one another and held stationary in overlying face-to-face relation and with said turns of each of said sensing sections substantially perpendicular to said turns of the other of said sensing sections;

an input member having an associated magnetic field which is substantially unvarying;

means for providing a planar surface substantially parallel with said planes of said sensing sections for supporting said input member for movement in the plane of said surface relative to said sensing sections with said magnetic field intersecting said sensing sections;

said input member being freely movable in said plane of said surface for inducing a voltage in each of said coils commensurate with the speed of movement of said input member relative to said each coil in a direction perpendicular to said turns of said sensing section thereof; and

means for integrating said voltages induced in said coils to produce two voltages representing the rectangular coordinates of position of said input member on said surface.

10. The apparatus of claim 9 in which each of said coils is coupled with the last-mentioned means through one winding of a transformer which produces a voltage at said each coil equal to and opposite in sign to the voltage induced in said each coil by transformer coupling between said each coil and the other of said coils.
